(57) **CLAIM**

The ornamental design for a seat speaker unit, as shown and described.

DESCRIPTION

FIG. 1 is a front, left perspective view of a seat speaker unit showing our new design;

FIG. 2 is a front, right perspective view thereof;

FIG. 3 is a front elevational view thereof; and,

FIG. 4 is a top plan view thereof.

The broken lines illustrating portions of the article or environmental structure form no part of the claimed design. The dot-dash broken lines defining the boundaries of the claimed design form no part of the claimed design.
